UNITED STATES PATENT OFFICE.

HARRY E. BURROUGHS, OF BOSTON, MASSACHUSETTS, ASSIGNOR TO LOUIS BECKWITH,
OF EVERETT, MASSACHUSETTS.

HAMMOCK.

Application filed January 26, 1921, Serial No. 440,092. Renewed January 18, 1923. Serial No. 530,998.

To all whom it may concern:

Be it known that I, HARRY E. BURROUGHS, a citizen of the United States of America, residing at Boston, in the county 5 of Suffolk and State of Massachusetts, have invented new and useful Improvements in Hammocks, of which the following is a specification.

This invention relates to infants' hammocks and more particularly to a folding hammock, that while having other and more general features of usefulness, is well adapted and designed for use in automobiles. A principal object of the invention 10 is to provide a folding hammock of this type, that is of simple and substantial construction, and also adapted to serve as an auxiliary seat on the floor of the car, when not required for use as a hammock. The 15 foregoing and other objects and advantages of the invention will more fully appear from the following detailed description, and the distinctive features of novelty will be pointed out in the appended claim.

20 Referring to the drawings:

Figure 1 is a side elevation of an infants' hammock embodying the invention opened and ready for use, a portion of the same being broken away;

25 Fig. 2 is side elevation thereof showing the hammock folded;

Fig. 3 is a perspective view of an enclosing case adapted to receive the hammock and to be used therewith when the 30 device is used as a seat; and

Fig. 4 is a perspective view of the casing from a different angle.

10 indicates a metallic frame composed of two U-bars 10^a, 10^b, the ends of which 40 are brought into proximity to each other and are pivoted as indicated at 11, 12 to U-shaped brackets 13 which permit a one-way folding of these members with respect to each other, and presenting its top as an 45 abutment preventing the members from swinging downward out of alignment from the position shown in Figure 1. The lower corners of these members are relieved or rounded as indicated at 14 so as to permit them to fold together as indicated in Fig. 50 2. The frame thus constituted may be sup-

ported in any suitable way either by suspension chains 15 engaged with the ends thereof, from an overhead support such as the top of the automobile, or it may be 55 supported from underneath by a suitable frame work (not shown). 16 indicates the hammock body which may be of canvas or other suitable flexible material. This body is provided along its upper edge with 60 spaced apart eyelets 17 which are engaged by rings 18 or like securing elements which pass through holes 19 of the frame and secure the body in depending relation to the frame. 20 indicates a mattress adapted 65 to be fitted in the hammock body. 21 indicates a casing or cover adapted to receive the hammock when folded as indicated in Fig. 2, it being understood that the mattress 20 will be doubled on itself and enclosed within the folded hammock body as 70 the hammock is inserted in the case 21. 22 indicates a top closure or flap adapted to be secured to close the case and fastened by suitable eyelets 23 or the like. This top 75 flap may be provided with a suitable handle 24. At one side of the case 21 I preferably provide a pocket 25 adapted to receive articles of apparel or other requisites for the care of the child. The case 21 may be made 80 of stout canvas or like material, and with the hammock and its mattress folded and placed therein, it is adapted to serve as a low seat when placed on the floor of the machine. I am aware that the invention 85 may be embodied in other specific forms without departing from the spirit or essential attributes thereof, and I therefore desire the present embodiment to be considered in all respects as illustrative and 90 not restrictive, reference being had to the appended claim rather than to the foregoing description to indicate the scope of the invention.

Having described my invention, what I 95 claim as new and desire to secure by Letters Patent is:

The combination with an infants' hammock composed of a metallic frame foldable midway of its length and formed of 100 two U-shaped bars pivoted for swinging with respect to each other and a flexible

hammock body depending therefrom with a mattress fitted therein, of a flexible case conforming in length to the length of said frame when folded and adapted to receive 5 said hammock body and frame with the mattress therein to constitute therewith a seat as set forth.

In testimony whereof I affix my signature in presence of two witnesses.

HARRY E. BURROUGHS.

Witnesses:

HENRY C. THOMSON,
LILLIAN K. HALEY.
